PROTECTIVE ABDOMINAL PLATE

William J. Marks, 5348 W. Lazy Hart St., Tucson, Ariz.

Filed Aug. 17, 1964, Ser. No. 81,322

Term of patent 14 years

(Cl. D3—10)

Fig. 1

I claim:

The ornamental design for a protective abdominal plate, substantially as shown.
